A. J. SINCLAIR,
CLARINET BARREL,
APPLICATION FILED JULY 5, 1921.

1,416,898.

Patented May 23, 1922.

UNITED STATES PATENT OFFICE.

ALFRED J. SINCLAIR, OF DAYTON, OHIO.

CLARINET BARREL.

1,416,898.

Specification of Letters Patent. Patented May 23, 1922.

Application filed July 5, 1921. Serial No. 482,817.

To all whom it may concern:

Be it known that I, ALFRED J. SINCLAIR, a citizen of the United States, residing at Dayton, in the county of Montgomery and State of Ohio, have invented certain new and useful Improvements in Clarinet Barrels, of which the following is a specification, reference being had therein to the accompanying drawing.

10 This invention relates to a clarinet barrel or the like.

In a clarinet the body of the instrument is connected with the mouth piece by a connecting member, commonly known as the barrel, which is provided with a longitudinal bore, enlarged at one end to receive the reduced end of the mouth piece and enlarged at the other end to receive the reduced end of the instrument. When the reduced end 20 of the instrument has been inserted in the barrel as far as it will go the end of the reduced portion thereof will engage the shoulder at the inner end of the recess or enlarged portion of the bore and a continuous passageway of uniform diameter will be provided. However, in practice it is frequently desirable to adjust the barrel lengthwise of the instrument for the purpose of tuning the instrument and when this is done the end of 25 the instrument is withdrawn from the shoulder and an annular cavity, or lateral pocket, is formed, which is in open communication with the bore, or passageway for the air and which not only seriously affects the tone of 30 the instrument but collects saliva and is otherwise objectionable. It has been proposed to remedy this in various ways, as by inserting washers in the recess, but this is 35 objectionable in operation and is not satisfactory in its results, and the player usually 40 endeavors to correct the faults in the tone with his lips.

The object of the present invention is to provide a barrel which can be adjusted on the instrument without destroying the uniformity of the bore or passageway through 45 the barrel.

A further object of the invention is to provide a barrel of this kind in which the cavity, 50 or pocket, between the end of the instrument and shoulder at the base of the recess will be automatically closed when the barrel is adjusted on the instrument.

Other objects of the invention will appear 55 as the device is described in detail.

In the accompanying drawings Fig. 1 is a

longitudinal sectional view taken through a barrel embodying my invention, showing the mouth piece and a portion of the instrument connected therewith; Fig. 2 is a side elevation, partly in section, of a barrel embodying my invention; Fig. 3 is a section taken on the line 3—3 of Fig. 1; Fig. 4 is a section taken on the line 4—4 of Fig. 1; Fig. 5 is a section taken on the line 5—5 of Fig. 1; and Fig. 6 is a detail of the slideable tube.

In these drawings I have illustrated one embodiment of my invention and have shown the same as applied to a clarinet of a standard construction. It will be understood, however, that this particular embodiment of the invention has been chosen for the purpose of illustration only and that the invention may take various forms and may be applied to instruments of various kinds.

In the form of the invention here illustrated I have shown the same as applied to a clarinet, a portion of which is indicated by the reference numeral 1 and has its upper end reduced, as shown at 2, to enter the recess 3 in the barrel 4. The barrel is provided with a longitudinal bore, or passage, 5, which is enlarged in its lower end to form the recess 3 into which the reduced end 2 of the instrument extends. The reduced end of the instrument is provided with the usual cork insert 6 which serves to form a tight joint between the barrel and the instrument and to hold the barrel in its adjusted positions on the instrument. At its upper end the bore 5 of the barrel is also enlarged to receive the reduced end portion of the mouth piece 7, which is of ordinary construction. The bore 5 and the enlarged end portion, or recess, 3 thereof are preferably lined with metal and, as here shown, the liner 14 for the bore and the recess is formed in a single piece but this is immaterial and the liner, if used, may be of any suitable character. The main portion of the bore through the barrel, as shown at 100 5, is made of a diameter slightly larger than the bore of the instrument end and there is mounted in this bore a thin metal tube 8 the inner diameter of which is substantially equal to the bore of the instrument end. 105 This tube is slidably mounted in the bore 5 and means are provided for maintaining the end thereof in contact with the instrument end at all times, thus causing the tube to bridge the pocket which would otherwise be 110 formed in the recess when the barrel is adjusted away from the instrument end. This

may be accomplished in various ways but, as here shown, I have provided the outer end of the tube 8 with a laterally extending flange 9 which is slidably mounted in the enlarged portion of the bore, or recess, and is acted upon by a spring 10 confined between the same and the shoulder at the inner end of the recess. It will be apparent, therefore, that the spring will tend at all times to move the tube toward the instrument end and if the barrel is moved away from the instrument end the tube will be maintained in engagement therewith and a passageway of uniform diameter provided at all times. The barrel is preferably provided with a shoulder 11 forming a recess 12 in which the spring is seated. When the barrel is moved toward the instrument end to the limit of its movement the flange 9 will engage the shoulder 11 and the spring will be confined wholly within the recess 12, thus positively limiting the movement of the barrel and avoiding any possibility of the spring being disarranged. The metal of the tube 8 is very thin so that it offers practically no obstruction to, or interference with, the passage of the air through the passageway, the tube being shown in the drawings as of an exaggerated thickness. The flange 9 preferably fits snugly within the recess 3 so as to form an air tight joint. Any suitable means may be provided to prevent the tube 8 being forced out of the barrel by the spring when the barrel is removed from the instrument. In the present construction, this is accomplished by terminating the liner 14 a short distance from the lower end of the barrel and inserting therein a collar, or a short liner, 13, the inner diameter of which is slightly less than the diameter of the liner and which, therefore, forms a narrow shoulder which is sufficient to check the outward movement of the flange and tube. The difference in the diameters of the liner and the collar 13 is very slight and need not be more than two-thousandths of an inch. Consequently, it does not interfere with the insertion of the instrument end in the barrel as the cork insert 6 will readily accommodate itself to this slightly reduced diameter.

The barrel in its outward appearance and general character is very similar to the ordinary barrel and it can be applied to any standard instrument in the same manner that the usual barrel is applied thereto. Further, the operation of the tube is wholly automatic and the tube accommodates itself to the position of the barrel on the instrument end without action of any kind on the part of the player, who adjusts the barrel in the same manner as he would adjust the ordinary barrel.

While I have shown and described one embodiment of my invention I wish it to be understood that I do not desire to be limited

to the details thereof as various modifications may occur to a person skilled in the art. It will be obvious that the tube might be interposed between any two parts of the instrument which are adjustable in the manner set forth, as, for example, between the barrel and the mouth piece, in which event the mouthpiece would have, so far as the present invention is concerned, the same functions as the instrument end and would 70 coact with the tube in the same manner; or the tube may be mounted in the mouth piece itself when the mouth piece is mounted directly on the instrument end.

Having now fully described my invention so what I claim as new and desire to secure by Letters Patent, is:

1. The combination with a portion of an instrument and a barrel having one end mounted thereon and adjustable longitudinally thereof and having its other end adapted to receive a mouth piece, of a tube slidably mounted in said barrel, and means for retaining said tube in contact with the instrument during the adjustment of the barrel thereon.

2. The combination with a portion of an instrument and a barrel having one end mounted thereon and adjustable longitudinally thereof, and having its other end adapted to receive a mouth piece, of a tube slidably mounted in said barrel, and a spring acting on said tube to hold the same in engagement with said instrument when said barrel is adjusted to different positions with relation to said instrument.

3. In a device of the character described, a body portion having a longitudinal bore, the end of which is enlarged to receive a part of an instrument and support said body portion for longitudinal adjustment thereon, a tube slidably mounted in the main portion of said bore, and means to automatically move said tube longitudinally of said bore when said body portion is adjusted on said instrument.

4. In a device of the character described, a body portion having a longitudinal bore provided with an enlarged portion in which a part of an instrument may be mounted for adjustment lengthwise of said body portion, a tube slidably mounted in the main portion of said bore, and means acting on said tube to maintain it in contact with the instrument when the body portion is adjusted lengthwise thereof.

5. In a device of the character described, a body portion having a longitudinal bore provided with an enlarged end portion to receive a part of an instrument and support said body portion for longitudinal adjustment thereon, a tube slidably mounted in the main portion of said bore and having a circumferential flange slidably mounted in the enlarged portion of said bore, and a

spring acting on said flange to move said tube toward the end of said body portion when said body portion is adjusted longitudinally on said instrument.

5 6. The combination with an instrument end having a longitudinal bore, and a barrel having a longitudinal bore of a diameter slightly larger than the diameter of the instrument end, the end portion of the bore of 10 said barrel being enlarged to receive the instrument end and support said barrel for longitudinal adjustment thereon, of a tube slidably mounted in the main portion of the bore of said barrel and having an internal 15 diameter substantially equal to the bore of the instrument end, said tube having a circumferential flange at its outer end to engage the instrument end, and a spring acting on said flange to retain the end of said 20 tube in engagement with said instrument end when the barrel is adjusted lengthwise thereof.

7. In a device of the character described, a barrel having a longitudinal bore, one end 25 of which is enlarged to receive a part of an instrument, a tube slidably mounted in the

main portion of said bore and having a flange slidably mounted in the enlarged portion of said bore, and a spring acting on said tube to move the same toward the outer 30 end of the enlarged portion of said bore, said enlarged portion of said bore having a shoulder near its outer end to limit the movement of said tube.

8. In a device of the character described, 35 a barrel having a longitudinal bore, one end of which is enlarged to receive a part of an instrument, a tube slidably mounted in the main portion of said bore and having a flange slidably mounted in the enlarged portion 40 of said bore, and a spring acting on said tube to move the same toward the outer end of the enlarged portion of said bore, said enlarged portion of said bore having two circumferential shoulders near the inner 45 end thereof, one of which forms a seat for said spring and the other of which forms a stop for said flange.

In testimony whereof, I affix my signature hereto.

ALFRED J. SINCLAIR.
